UNITED STATES PATENT OFFICE

2,483,355

FABRIC GUIDING DEVICE

Eugene St. Pierre, Pawtucket, R. I., assignor to
Hemphill Company, Central Falls, R. I., a corporation of Massachusetts

Application March 11, 1948, Serial No. 14,321

2 Claims. (Cl. 66—147)

1

Sheer, circular knit hosiery is generally produced individually as distinguished from string work, each stocking being run off the needles when completed. When a stocking is begun, the initial fabric is very short and light. As it lengthens, it is not likely to drop into the cylinder as it would if it were heavier but tends to be crowded upward into a crushed mass with the result that its loop structure is upset. This is particularly so when the knitting is loose and it must be loose to provide adequate size for the welt or stocking top. To counteract this, the inside of the upper part of the cylinder has been fitted with a short inwardly extending fin positioned at such an angle that it wipes against the fabric and tends to move it downward into the cylinder. However, such a fin cannot begin to act upon the fabric until it has acquired considerable length and with respect to light fabric, it is more likely to hold it up than cause it to drop. The device of this invention may supplement and make effective the fin just mentioned or it may be used alone. The form of the device illustrated herein for descriptive purposes is designed for use on a hosiery knitting machine of the Banner type. However, it can be used on other types of circular hosiery machines or upon circular knitting machines in general.

In the drawing:

Fig. 1 is a plan view of certain parts of a Banner knitting machine to which the invention has been applied;

Fig. 2 is an elevation also illustrating the invention;

Fig. 3 is an elevation illustrating certain of the parts by which the device is operated;

Fig. 4 is a detail showing how the invention guides the fabric downwardly into the cylinder;

Figs. 5 and 6 are, respectively, plan and elevational views showing the details of the connections between certain of the operating levers.

As shown in Fig. 1, the device consists of a curved finger 1 suitably pivoted as at 2 as to be swingable in a plane slightly inclined downwardly towards the cylinder and so that the end 3 of finger 1 will follow an arcuate path across the needle cylinder from the idle position shown in dotted line in Fig. 1 to the fully operative position shown in full line. In order that the finger may be as close to the knitted fabric as possible and, if a dial is used so that it can pass between the dial and the cylinder needles, it is preferably positioned so as to cross the needle circle at the point where the needles are lowest, i. e., at their casting off point (see Fig. 4).

2

Finger 1 may be operated, as above described, by mechanism shown in Figs. 1, 2 and 3. It consists of a rod 4, one end of which is pivotally connected to the finger as at 5 and the other end of which is pivoted at one end 6 of a bell crank 7. At the other end 8 of bell crank 7 is pivotally connected a rod 9 which extends downwardly to a connection 10 at one end of a pivoted lever 11. At the other end 12, lever 11 is connected with a rod 13 which extends downwardly to one end 14 of another lever 15, the thin end 16 of which is connected to a rod 17 which in turn connects a rocker 18 adapted to be operated by a cam drum 19. Preferably, the cam 20 upon this drum 15 is provided with a series of steps such as 21 and 22 (Fig. 3) so that the finger 1 can be given a series of progressive inward movements.

At the start of the stocking, the drum is so arranged that rocker 18 rides upon cam 20 so that finger 1 is in its inactive outward position shown in dotted line in Fig. 1. Drum 19 is so operated that after a few courses of fabric have been knit rocker 18 moves down onto step 21 and finger 1 is swung by spring 23 across the needle circle so that it overlies the fabric being knit. After a desired amount of additional fabric has been knit, the length of which is determinable by experiment and which will vary with different yarns and weights of yarn and the character of the knitting, drum 19 is operated so as to permit rocker 18 to pass onto the lower step 22 of the cam drum. This will cause finger 1 to swing inwardly still further thus following the fabric into the cylinder and guiding it downwardly at a small angle. After still more fabric has been knit, drum 19 permits rocker 18 to drop to the surface 24 of the drum which allows the full inward swing of finger 1 as shown in full line in Fig. 1 and also as illustrated in Fig. 4. Of course, the cam on drum 19 may have more or fewer steps so that finger 1 will follow the lengthening fabric more or less frequently and closely. This is a matter of choice. Two steps have been found to be adequate for the control of the sheerest and lightest

Since the finger moves in a downwardly inclined direction as it swings further and further into the cylinder, it will be evident that the fabric will be guided downwardly by it and will be unable to bunch at the top of the cylinder. The elimination of this bunching makes it possible to knit as loosely as desired and yet produce a loop structure as perfect as that of the other parts of the stocking. Without this device, loose knitting at the beginning of the welt of a sheer stocking

is subject to sharp limitations since looser knitting results in distorted fabric as a result of the bunching up of the fabric referred to. In practical terms, this means that the size of a stocking at the top is determined by the limitations of the machine rather than by the requirements of the wearer.

Assuming that the cylinder rotates in the customary counter-clockwise direction, surface 29 of finger 1 is curved, preferably, as shown in Fig. 1 so that a convex surface is presented to the fabric which will tend to spread it gently as a further safeguard against bunching.

A novel form of coupling is also utilized in this invention. As shown in Figs. 3, 5 and 6, 15 each end of lever 15, end 14, for example, is cut away to produce a tongue 25 fitted near its tip with a laterally projecting set screw 26. The corresponding end 27 of a connection such as rod 13 is forked so as to pass on either side of tongue 25 sufficiently to permit the ends of the fork to be closed by a pin or roller 28 thus closing the fork around tongue 25. Set screw 26 maintains the coupling and its removal permits separation of the coupled parts without disturbing their individual adjustments or proportions.

I claim:

1. In a circular, independent needle, knitting

machine having a cylinder, means for guiding knitted fabric which includes a finger having a portion projectable into said cylinder across said needle circle along an arcuate path said finger being adapted to contact knitted fabric and guide it downwardly into said cylinder and prevent it from bunching and means for so projecting said finger in a plurality of progressive, timed steps.

2. In a circular, independent needle, knitting machine having a cylinder, means for guiding knitted fabric downwardly within the cylinder as claimed in claim 1 and in which the means for so projecting said finger includes a drum provided with cams and operating linkage between said cams and said finger through which the progressive projection of said finger is controlled by said cams as to distance and time.

EUGENE ST. PIERRE.
